(57) **CLAIM**

The ornamental design for the communication device, as shown and described.

DESCRIPTION

FIG. 1 is a perspective view of an ornamental communication device.

FIG. 2 is a front view thereof.

FIG. 3 is a rear view thereof.

FIG. 4 is a first side view thereof.

FIG. 5 is a second side view, opposite the first side view, thereof.

FIG. 6 is a bottom view thereof; and,

FIG. 7 is a top view, opposite the bottom view, thereof.

The broken lines immediately adjacent the shaded areas represent the bounds of the claimed design while all other broken lines are directed to environment and are for illustrative purposes only; the broken lines form no part of the claimed design.
